LOUIS STEINBERGER, OF BROOKLYN, NEW YORK.

CONNECTING DEVICE FOR ELECTRICAL CONDUCTORS.

1,206,738.

Specification of Letters Patent. Patented Nov. 28, 1916.

Application filed May 17, 1912, Serial No. 698,008. Renewed November 1, 1916. Serial No. 128,939.

To all whom it may concern:

Be it known that I, LOUIS STEINBERGER, residing at Brooklyn, in the county of Kings and State of New York, have invented certain new and useful Improvements in Connecting Devices for Electrical Conductors, of which the following is a specification.

This invention relates to a novel construction of binding posts, said posts being particularly adapted for use in the manufacture of distributor blocks such as are commonly employed in connection with magnetos for gas engine operation. These blocks are formed of a suitable material such as "electrose" or hard rubber, and the binding posts are adapted to be molded almost wholly within their bodies.

I seek, among other things, to provide a binding post which is compact and extremely simple in construction, which may be manufactured at low cost, and which is capable of withstanding a considerable degree of maltreatment, and which will form a positive connection between itself and the conductor terminal which may be connected to it, and which will permit of the terminal being connected to it by an extremely simple operation, and which will hold the terminal against accidental displacement.

Among the objects to be accomplished by the aid of my invention are the following:

I. To provide a binding post which may be embedded in the material of the distributor block so as to have a very small portion of itself projecting above the surface of the block, so that portions of the insulating material comprising the block may be formed into barriers of small size and yet of sufficient size to entirely exclude the possibility of passage of current from one post to another.

II. To provide the exterior of the binding post within the material of the block, with a suitably roughened corrugated surface adapted to more firmly grip and be held within the molded material.

III. To provide a tubular member adapted to be molded within the insulating material of the block, and having a metallic conductor leading from preferably the bottom wall thereof to one of the contact members of the distributor block.

IV. To provide within the tubular member referred to, a detachable mechanism comprising a clamp attached to receive and

hold a conductor terminal above the outer end of the tubular member.

V. To provide a closure for the upper end of the tubular member referred to, said closure having a substantially central aperture extending longitudinally of the tubular member, adapted to slidably receive a stem having a head formed upon its upper end and having means engaging its lower end within said tubular member for yieldingly maintaining its head in contact with said closure to form a spring clamp between said head and closure.

VI. To provide the head of the stem referred to with a semi-spherical convexed under surface, and to provide a conductor terminal with a semi-spherical depression adapted to be engaged and detachably retained by the semi-spherical portion of said head.

VII. To provide the head above mentioned with a semi-spherical convexed under surface and to provide the closure above mentioned, with a semi-spherical convexed upper surface and to provide a conductor terminal comprising a slotted plate having a semi-spherical depression formed in one of its surfaces, the structure being such that said conductor terminal may be reversed at will for disposing the depressed portion thereof in engagement with either of the convexed portions of the clamp.

VIII. Further, to provide, in combination with the tubular member above referred to, a closure for one of its ends and a clamp member engaging said closure, said clamp member having a stem extending through said closure, a compression spring surrounding said stem, having its upper end engaging the under surface of said closure, and a head adjustably retained on the lower end of said stem engaging the lower end of said spring whereby the clamping power of said clamp may be adjusted at will.

IX. To provide a binding post comprising a clamp adapted to receive and detachably retain the conductor terminal, said clamp comprising a spring, means for adjusting the tension of said spring for determining the clamping power of said clamp, and said adjusting means being disposed within a casing whereby the same may not be tampered with by unauthorized hands.

X. To provide a binding post particularly adapted for being molded within the

material of a distributor block, said post being of such a construction as to be adaptable to being positioned either upon the flat face of the block or upon the edge surfaces thereof, and to have so little of itself in evidence as to permit of the use of a considerable number of posts being molded within a single block of ordinary size without overburdening or complicating the appearance of the structure, and to permit of the posts being disposed in relatively close proximity to the respective contact points to which they are electrically connected.

XI. To provide a binding post comprising a clamp, to provide a conductor terminal adapted to be clamped in such clamp, and to shape the clamping faces of the clamp and the conductor terminal in such manner as to coöperate to effect a substantially perfect setting of the conductor terminal between the clamp faces, without especial care on the part of the operator.

Other objects and aims of the invention, more or less broad than those stated above, will be in part obvious and in part specifically referred to in the course of the following description of the elements, combinations, arrangements of parts, and applications of principles constituting the invention, and the scope of protection contemplated therefor will be indicated in the appended claims.

In the accompanying drawings, which are to be taken as a part of this specification, and in which I have illustrated a merely preferred form of embodiment of the invention: Figure 1 is an elevational view of a distributor block in connection with which this invention is particularly adapted to be employed, and illustrating the several binding posts, formed in accordance with the provisions of this invention, fitted thereto, shown partly by dotted lines, some of said parts being shown in top plan, a part of said view being shown in a vertical section for better disclosing the relative position of one of the binding posts within the body of the insulating material of which the distributor block is molded; Fig. 2 is a view taken from the opposite side of the distributor block; Fig. 3 is a vertical, transverse, sectional view through the distributor block; Fig. 4 is a perspective view of the several parts, of which one of the binding posts is composed, said parts being shown disassembled and aligned to better illustrate the method of assembling the structure; Fig. 5 is a detail view of a conductor terminal such as is used in connection with the binding post structure illustrated; and Fig. 6 is a sectional view on the plane of line 6-6 of Fig. 5.

Referring to the drawings by numerals, 1 indicates the body portion of the distributor block, which it will be understood,

comprises a fictile material, such as "electrostone," porcelain, or the like, and which is molded into form, and provided with suitable reinforced apertures 2, whereby the block may be attached to a magneto, in a convenient position for coöperation with the moving armature thereof, such position being the same as is common in the construction of devices of this character.

The distributor block is formed with a circular recess 3 in its rear face within which a rotating brush (not shown) is received and rotatably mounted in a reinforced bearing 4 molded within the body portion of the distributor block centrally of the circular depression 3. Arranged at evenly spaced points about the bearing 4 and within the depression 3 are a plurality of pockets 5 adapted to receive contact members (not shown) for successive engagement by the rotating brush, all of which is well known in the art.

Each of the pockets 5 is electrically connected with a binding post 6 by a metallic conductor 7 embedded entirely within the body portion of the distributor block and being wound or otherwise electrically connected to the respective pockets by one of its ends, and having its other end electrically connected with the respective binding post. 90 Each of the binding posts, of which I have shown six, one for each of the contact points in the distributor block, is identical in shape, construction, in its manner of attachment to the insulator block and in the method by which the metallic conductors 7 are connected thereto, and each of said binding posts comprise a tubular member 8 having its entire bulk embedded within the body portion of the distributor block, so that its upper end lies flush with the surface of the material of the block. The exterior surface of the member 8 is preferably roughened, as at 9, whereby the same is more firmly held by the fictile material with which it comes into engagement. The inner end of the member 8 is closed by a wall 10 and the respective conductor 7 is attached to said wall, preferably by being extended through a suitable aperture 11 formed therein, soldered or otherwise positively electrically connected to said wall, and thus to the body portion of the binding post. The upper end of the member 8 is internally threaded and fitted with a closure 12 having external threads engaging the threads of said member 8, and being thereby easily attached or removed at will. The closure 12 is formed with an enlarged head portion 13 providing a shoulder 14 adapted to engage the upper annular surface of the member 8, and the upper surface of said head 13 is rounded into semi-spherical shape as at 15. Extending substantially centrally through the closure 12 longitudinally of the member 8 130

is an aperture 16 adapted to receive a stem 17 which is formed at its upper end with a head 18. Within the tubular member 8, below the closure 12, a compression spring 19 encircles the lower portion of the stem 17 and is adapted to be compressed between the under surface of the closure 12 and the upper surface of a nut or head 20, which is threaded and thus adjustably held at the lower end of the stem 17. Obviously, rotation of the nut 20 about the stem 17 will compress, or permit extension of, the spring 19, and thus effect an adjustment of the degree of pressure in the clamp formed between the under surface of the head 18 and the upper surface of the head 13 of the closure 12.

It will be noted that in order to effect an adjustment of the degree of pressure exerted by the spring 19, it will be necessary to grasp both the head 18 and the head or nut 20, and that to do this is impossible so long as the head 20 is in position within the member 8. That is to say, that it would require that the closure 12 be designedly removed from its engagement with the member 8 before any change could be effected in the compression value of the spring. This point is valuable in that it obviates all likelihood of accidental relief of the stress in the spring and a consequent accidental detachment of the conductor terminal which engages the binding post.

The under surface of the head 18 is rounded semi-spherically in the same manner as is the upper surface 15 of the closure 12, and said opposing convexed surfaces, being drawn steadily together under compression of the spring 19 form a clamp peculiarly adapted for retaining a conductor terminal particularly formed to receive said convexed surfaces. As illustrated in Figs. 1, 5 and 6, the conductor terminal adapted for engagement with the binding post described, comprises a substantially flat plate 21 having its one end electrically connected at 22 to the conductor 23 in a well known manner, and having its opposite end enlarged and formed with a slot 24, providing the legs 25 adapted to straddle the stem 17 when the terminal is being forced to position between the clamping surfaces of the binding post. The inner end of the slot 24 is preferably semi-circular in form and a semi-spherical depression 26 is formed in the surface of said plate concentrically of the center of the semi-circular portion of said slot, and said semispherical depression is adapted to be engaged by the correspondingly semi-spherical convexed portion of either the head 13 or the under surface of the head 18, said conductor terminal being thus reversible to dispose the depressed portion 26 in engagement with either of said convexed portions.

The conductor terminal is preferably of relatively thin material and the semi-spherical depression 26 therein is formed by pressing the material in a die so that the surface of said terminal opposite the semi-spherical depression is semi-spherically convexed substantially concentrically with the semi-spherical depression. Thus it is apparent that upon introducing the terminal between the opposing faces of the clamp, it will not be necessary for the operator to exercise especial care in forcing the terminal to a positively defined final position. All that is required is for the terminal to be introduced just sufficiently far for the semi-spherically convexed surface of either of the opposing members of the clamp to engage a portion of the semi-spherically shaped depression in the terminal whereupon the yielding pressure of the clamp will induce the terminal to move with a cam or wedge-like action into a substantially perfect set with the clamp.

I am aware that it has been heretofore suggested in the art to provide clamping members between which a terminal may be engaged in somewhat the same manner as I have disclosed, but within my knowledge such constructions having necessarily required the movement of the terminal into a single fixed position relatively to the clamping members ere the connection between the clamp and the terminal could be considered as being of its maximum efficiency either electrically or mechanically. By arranging the clamping surfaces of my binding post 100 of hemi-spherical convexed shape, and providing the semi-spherical depression in one surface of my conductor terminal, I have simplified the construction and have entirely avoided the necessity for careful adjustment. 105 The parts coöperate in such manner as to automatically effect a substantially perfect setting of the conductor terminal between the clamp faces.

The closure 12 with the stem and head 17 and 18 respectively, and the spring 19 and head 20 are readily removed, as an entirety, from connection with the tubular member 8 by the simple rotation of the closure 12 to disengage the same from the threads of the member 8, but while in place, said closure becomes in effect, a part of the member 8, that is to say, it assumes a fixed relation to said member and performs its functions in the same manner as if it were an integral 120 portion thereof.

Attention is particularly directed to the fact that the binding post described, though of unquestioned effectiveness in its retention of a conductor terminal and the consequent thorough electrical connection between the post and the terminal, and of unquestioned general practicability, is so designed that it projects only a very slight distance above the surface of the material 130

in which it is embedded; and that the conductor terminals, and their method of application, are so simple that a post, even with a terminal attached, is so small and neat as to admit of the use of any reasonable number on a single block without complication and without interfering with the positioning of the posts in close proximity to the contact points with which they are individually connected.

10 In a distributor block such as that described, some of the binding posts are arranged along the upper surface thereof at spaced points, and said upper surface is 15 formed with suitable barriers 27, which are designed to positively prevent the arcing over of current from one binding post to the other. The binding posts described extending as they do, only a short distance 20 above the surface of the distributor block materially enhance the value of the barriers for their purpose, as said barriers may readily extend above the uppermost surface of the binding post.

25 As many changes could be made in the above construction, and many apparently widely different embodiments of this invention could be made without departing from the scope thereof, it is intended that all 30 matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention, which as a matter of language, might be said to fall therebetween.

40 Having thus described my invention what I claim as new and desire to secure by Letters Patent, is:

1. In a device of the class described, the 45 combination with a tubular metallic casing open at one end adapted to be fixed within a body of insulating material or the like so

that its open end opens through the surface of said body of insulating material, of a closure for said open end having an aperture therethrough, a rod extending through said aperture beyond the inner end of said closure into the open space within said casing, said rod being slidable through said aperture and having a head at its outer 55 end, spring means disposed within the casing engaging between the inner end of said rod and the inner end surface of said closure to urge said head toward the outer surface of said closure so as to comprise a clamp 60 for attaching a conductor terminal between said head and the outer surface of said closure, and means whereby said closure with said rod and the parts carried thereby forming the terminal retaining clamp is 65 detachably connected to said casing so that the terminal retaining clamp may be detached as an entity from said casing at will.

2. The combination with a sheet metal conductor terminal pressed to form a semi-spherical depression in one surface thereof and a substantially concentrically disposed semi-spherically convexed portion at the opposite surface thereof, of a binding post comprising a clamp, one of the clamping 70 faces of which is semi-spherically convexed to engage within the semi-spherical depression in the conductor terminal whereby to urge the conductor terminal toward a given central position between the surfaces of the 75 clamp, and the semi-spherically convexed opposite surface of the terminal by presenting a continuously concentric rounding surface to the other clamping face of the clamp 80 serving to facilitate and assist the sliding 85 movement of the terminal into said given central relation with the binding post.

In testimony whereof I affix my signature in the presence of two witnesses.

LOUIS STEINBERGER.
